UNITED STATES PATENT OFFICE.

FRANK KLEINSCHMIDT, OF BUFFALO, NEW YORK.

DRYING APPARATUS.

1,179,192.

Specification of Letters Patent. Patented Apr. 11, 1916.

Application filed March 28, 1912. Serial No. 686,723.

To all whom it may concern:

Be it known that I, FRANK KLEINSCHMIDT, a citizen of the United States, and resident of Buffalo, in the county of Erie 5 and State of New York, have invented new and useful Improvements in Drying Apparatus, of which the following is a specification.

This invention relates to a drying apparatus for drying tankage, garbage, graphite, sand, malt, grain and other material, and it has for its primary object the provision of a comparatively simple and inexpensive apparatus which will permit of drying material in batches or continuously, as desired.

Other objects are to so construct the apparatus that the heat applied thereto will be distributed so as to come in contact with every portion of the surface of the containing drum or receptacle, and to distribute the heat approximately evenly to said surface.

A further object of my invention is to provide means to apply the heat directly to the material to be dried or indirectly through 25 the wall of the containing drum or receptacle, as desired; to provide means for the escape of vapor and fumes from the material being dried; to direct the fumes to the fire so as to be consumed thereby; to condense the vapor passing from the material being dried; and to automatically discharge the water of condensation into a sewer or otherwise.

Further objects of my invention are to 35 provide an apparatus of this kind by means of which an increased capacity is obtained over other drying apparatuses now in use; and to otherwise improve on the construction and arrangement of parts.

With these ends in view, the invention consists in the novel features of construction and in the arrangement and combination of devices and parts to be hereinafter described and particularly pointed out in the 45 subjoined claims.

In the drawings, Figure 1 is a central longitudinal section through an apparatus constructed according to my invention. Fig. 2 is a rear end view of the same. Fig. 3 is 50 a transverse section taken on line 3-3, Fig. 1.

Referring now to the drawings in detail, like numerals of reference refer to like parts in the several figures.

The reference numeral 4 designates the

material-containing drum or receptacle which is located within a furnace 5 constructed in the main of brick, the ends of said drum or receptacle extending from opposite ends of said furnace. 60

The furnace has the usual side walls 6, a top wall 7, a front wall 8, and a rear wall 9. Between said front and rear walls is located a bridge wall 10 and between said bridge wall and said front wall is arranged the 65 fire-place 11 having underneath it the usual ash pit 12 separated from said fire-place by the grate 13. Extending rearwardly from said front wall and above said grate is a distributor arch or diffuser 14, which is 70 preferably constructed of fire brick and has a series of openings 15 extending therethrough. The rear end of said distributor arch or diffuser is separated from the bridge wall by a narrow passage 16. The front 75 wall 8 has openings 17 formed therein for access to the fire place, which openings are closed by door 18 and an opening 19 is formed in said front wall for access to the ash pit, said opening 19 being closed by 80 door 20.

Secured exteriorly to the front and rear walls 8, 9 of the furnace are annuli 21, 22, respectively, through which pass the ends of the drum 4. Said drum is preferably cylindrical and open at opposite ends and near each end it has secured therein a spider 23 in the hub of which are secured shafts 24 projecting from opposite ends of the drum and passing through heads 25 fixedly supported and closing the open ends of said drum. At opposite ends of the furnace are arranged frames 26 having secured thereto bearing boxes 27 which may form part of the heads 25 and in which said shafts 24 are 90 journaled. The shaft 24 at the front of the furnace has a driving pulley 28 secured thereto around which passes a belt 29 driven in any suitable manner. 95

Arranged within the drum 4 is a conveyor 30 so arranged therein that it conveys the material from one end of the drum to the other, preferably from the forward end to the rear end thereof, said conveyor being preferably constructed of a spirally 105 formed bar secured to the inner face of the drum, as clearly shown in Fig. 1.

In the head 25 at the rear end of the drum an opening 31 is provided and secured to said head is a flue 32 having com- 110

munication with the interior of said drum through said opening. The drum is so arranged within the furnace that it has a heat space 33 entirely surrounding it and opening into said heat space is a smoke stack 34, said stack being fitted into the top wall 7 of the furnace and having the flue 32 connected therewith. In said smoke stack is arranged a damper 35 and a similar damper 36 is arranged in the flue 32.

An opening 37 is formed in the head at the front end of the drum and secured to said head is a feed-tube 38 adapted to feed material into said drum through said opening. Said feed-tube may be led to any desired point and as illustrated in the drawing is preferably directed into the story above the furnace-room. In leading said tube into the story above, it passes through the floor 39 and formed in said tube directly above the floor is a feed opening 40 which may be closed by gate or door 41, as shown. Upon opening said door the material to be dried may be shoveled from the floor 39 directly into the feed-tube so that it gravitates into the drum. In this manner the drum may be supplied with the material to be dried in batches so that after the desired quantity is delivered into the drum the gate or door 41 may be closed.

I have made provision for a continuous feed of the material to be dried by connecting the feed-tube above the opening 40 with a vertically disposed tube 42 having connection at its upper end with a horizontally-disposed tube 43 provided with a conveyer 44 of ordinary construction, said conveyer being driven by means of a belt 45 and pulley 46 secured to the conveyer shaft 47, or if desired, in any other manner, and leading to the conveyer-tube 43 is a hopper 48 which may be of any desired size or into which may be fed from a general supply the material to be dried. When the material passes from the hopper 48 into the conveyer-tube, the conveyer 44 delivers the same into the tube 42 and feed-tube 38 so that it is fed continuously into the drum 4.

The upper end of the feed-tube terminates at a point above the tube 42 and has secured thereto the suction inducer 49 which is preferably cylindrical in shape and provided with a conical portion 50 and it has a steam supply pipe 51 arranged therein which terminates in a pointed nozzle 52 occupying a position centrally in the restricted or small end of said conical portion. Secured to the restricted or small end of said conical portion is a flaring tube section 53 which has connection with a vertically-disposed flue 54 directed downwardly for connection with the top wall of a tank 55, said tank having depending from its top wall a baffle-plate 56, at one side of which said tube 54 is arranged to enter the tank

and on the other side of said baffle-plate is a pipe or flue 57 which is directed to a point underneath the fire grate 13 of the furnace, as at 58. The tank 55 is supplied with water, the level of which is governed by a trap 59 connected to the tank at or near its lower end, as at 60. Secured to said trap at its upper end is a vent-pipe 61 which serves to prevent siphoning of the tank 55.

Arranged in the upper end of the vertically-disposed flue 54 is a condenser 62 which comprises a cold water pipe 63 and a perforated sprinkler head 64.

The head at the rear end of the drum 4 is provided with a discharge opening 65 closed by a door 66 which is held in closed position by an arm 67 adapted to engage a keeper 68 secured to the rear wall 9 or the annulus 22 applied to said rear end.

The operation of the apparatus is as follows: The heat of the fire within the fireplace is directed upwardly through the narrow space 16 between the bridge wall and the distributor arch or diffuser and also through the openings 15 in said diffuser, said arch or diffuser serving particularly to prevent the front end of the drum being subjected to a greater degree of heat than the rear and consequently diffuses the heat so that the proper proportion will pass rearwardly and upwardly along the drum; the heat therefore is directed to all parts of the heat space 33 and serves to heat and dry the material within the drum. The damper 35 in the smoke-stack checks the escape of heat and when the damper 36 in the flue 32 is closed the heat is prevented from passing through said flue. During the heating of the drum, the latter is rotated so as to present new portions of the material to the wall of the drum and also to direct the material rearwardly toward the rear head 25. The pitch of the spirally arranged bars within the drum being arranged to render the rearward passage of the material slow and by the time the material reaches the rear end of the drum it will be thoroughly dry, when it may be discharged through the openings 65 by opening the door 66 thereof. The fumes and moisture from the material escapes through the feed-tube 28 and owing to the suction inducer 49 being arranged at the end of said tube the escape of the moisture and fumes is accelerated. The steam escaping from the nozzle 52 passes with the moisture and fumes down the tube 54 and is condensed by the spray of cold water coming in contact therewith from the sprinkler head 64, the moisture and water settling in the tank 55 in which the water is maintained at a constant level by the trap 59 and as the level of the water rises by reason of water flowing into said tank it overflows the trap and passes away to a sewer or may otherwise be disposed of,

the vent-pipe 61 at the upper end of the trap 59 serving to prevent siphoning of the water from the tank. The fumes entering the tank 55 pass around the baffle-plate 56 and escape through the pipe 57 which leads it into the fire to be there consumed. If desired, the heat of the furnace may be directed through the drum so as to come in direct contact with the material being dried, this being accomplished by opening the damper 36 in the flue 32 and closing the damper 35 in the smoke-stack. When the dampers are thus arranged the heat escapes with the fumes and moisture through the feed tube.

It will be apparent from the foregoing that changes in minor details of construction and departures from the exact arrangement of the parts may be resorted to without departing from the spirit of my invention or sacrificing any of the advantages thereof and, furthermore, parts of the apparatus may be used without others as the functions of each will be performed fully as well as when all are combined.

Having thus described my invention, what I claim is,—

1. In a drying apparatus, the combination with a furnace having a fire-place, a perforated wall above said fire-place and a bridge wall at the rear end of said fire-place separated from the rear end of said perforated wall by an intervening space, of a drum rotatable in said furnace in a plane above said perforated wall and having a feed opening and a discharge opening.

2. In a drying apparatus, the combination with a furnace having a fire-place, a perforated wall above a portion of said fire-place and a bridge wall forming the rear end wall of said fire-place, the rear end of said perforated wall being spaced from said bridge wall, of a drum rotatable in said furnace above said perforated wall and above the space between said perforated wall and said bridge wall, said drum extending in

rear of said bridge wall and having a feed opening and a discharge opening.

3. In a drying apparatus, the combination with a furnace having a fire-place, a perforated wall above said fire-place and a bridge wall at the rear end of said fire-place separated from the rear end of said perforated wall by an intervening space, of a drum rotatable in said furnace in a plane above said perforated wall and having a feed opening and a discharge opening, all products of combustion escaping from the rear end of said fire-place passing upward through said intervening space.

4. In a drying apparatus, the combination with a furnace, of a drum rotatable in said furnace, a feed tube connected to said drum, a suction inducer connected with said feed tube, a condenser connected with said suction inducer, and a tank connected with said condenser, said tank having a water escape and an escape for fumes and said latter escape being directed into the furnace beneath its fire-place.

5. In a drying apparatus, the combination with a furnace having a smoke-stack provided with a damper, of a drum rotatable in said furnace and having a fixed head at one end provided with a feed-tube, said drum having also a fixed head at its other end provided with a discharge opening, means within said drum for conveying the material from the first-mentioned end to its other end, and a flue connecting said second-mentioned head with the smoke-stack and having a damper therein, said flue receiving the heat from said smoke-stack and directing it into said drum.

In testimony whereof, I have affixed my signature in the presence of two subscribing witnesses.

FRANK KLEINSCHMIDT.
